ARTICLE COMPRESSING MECHANISM FOR
WRAPPING MACHINESOscar Sandberg, Defiance, Ohio, assignor to
Lynch Manufacturing Corporation, Defiance,
Ohio, a corporation of Ohio

Application February 17, 1942, Serial No. 431,210

11 Claims. (Cl. 107—15)

My present invention relates to a compressing mechanism for articles such as candy bars or the like being wrapped in a wrapping machine, the mechanism effecting a compression of oversize articles so that they may pass properly through the wrapping machine without clogging it, the present invention being useful in connection with a wrapping machine of the kind shown in my copending application, Serial No. 317,370, filed February 5, 1940.

One object of the invention is to provide a simple mechanism which operates in timed relation with the wrapping machine and is operable to compress an oversized candy bar or the like while the conveyer which carries it to wrapping position is in a stopped position.

A further object is to provide, in connection with an intermittently movable conveyer for candy bars and the like, a pair of pressure plates operable to engage the top and end of a candy bar in a pocket of the conveyer if such candy bar is oversize and would therefore cause clogging of the machine, the pressure plates effecting a compression of the bar to a size permitting ready passage thereof through the machine providing it is not too much oversize, safety stop devices of my copending application taking care of bars which are still too much oversize after the pressure plates have operated and effecting automatic stoppage of the wrapping machine.

Still a further object is to provide an article compressing mechanism operable to compress an article in a pocket of a conveyer to reduce the size of the article so that it may pass freely between a pair of fences without dragging on them and so that its height in the pocket is less than a predetermined measurement, thus insuring that the article may be properly wrapped without clogging or otherwise interfering with the operation of the wrapping machine.

With these and other objects in view, my invention consists in the construction, arrangement and combination of the various parts of my device whereby the objects contemplated are attained, as hereinafter more fully set forth, pointed out in my claims and illustrated in the accompanying drawings. Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawings, in which:

Figure 1 is a plan view of a portion of the feed end of a wrapping machine with my article compressing mechanism applied thereto;

Figure 2 is a sectional view on the line 2—2 of Figure 1 showing the compressing mechanism in normal position, and

Figure 3 is a similar sectional view showing it in compressing position.

On the accompanying drawings, I have used the reference character F to indicate generally a frame. The frame F has a pair of stationary rods 10 and 12 on which various mechanisms of the machine are mounted. One such mechanism is an article conveyer including a conveyer chain 13 and channel shaped pockets 14. The pockets 14 slide on supporting bars 15 which are supported by transverse rods 16 and 17 on the supporting rods 10 and 12. In Figure 1, the pockets 14 are traveling from a position where they receive cards C and articles such as candy bars B in the direction of the arrow 18 toward a position where the cards and bars are wrapped within a pair of wrappers, as fully disclosed in my copending application.

The mechanism for operating the conveyer 13—14 is such that it causes intermittent movement of the pockets 14, whereas an intermittent movement is also provided for a rock shaft 19, which shaft rocks at a time when the pockets 14 are stationary, as also fully disclosed in my copending application.

In some instances the candy bars B are too large to be properly wrapped in the machine and if inserted in the pockets 14 would clog the conveyer 13—14 or the wrapping mechanism of the machine. To eliminate such undesirable operation of the machine, I provide a pair of pressure plates 20 and 21 for compressing the tops and ends respectively of the bars B. Articles such as chocolate candy bars either with or without nuts in them may be suitably compressed by the pressure plates 20 and 21 so as to reduce their size to one which will permit them to pass through the machine without clogging it, unless the bars are too much oversize. If after compression they are still too much oversize, other safety devices operate to stop the wrapping machine, as shown in my copending application referred to and in another copending application, Serial No. 435,781 filed March 23, 1942.

For operating the pressure plates 20 and 21, I provide the following described mechanism: An arm 22 is mounted on the rock shaft 19. It is connected by a link 23, a bell crank 24 and a

link 25 with a bar 26. The bar 26 has the pressure plate 20 secured thereto as by screws 27 and is oscillatable on a stud 28. The bar 26 is retained on the stud by a collar 29 and is provided with an arm 30 whereby the bar 26 and the arm 30 form a bell crank. A link 31 is pivoted to a shouldered bolt 32 which is adjustable in a slot 33 of the arm 30 whereby the degree of movement of the link 31 may be adjusted. The link 31 is connected with a bracket 34 which in turn is connected with the pressure plate 21. The pivot joints at 32 and between the elements 31 and 34 are sufficiently loose to prevent binding during operation.

The pressure plate 21 is secured to an arm 35 by means of screws 36. The arm 35 is formed on a hub 37 which is oscillatable on a stud 38. The stud 38 is rigidly mounted on a plate 39 secured as by screws 40 to the frame F or some part rigid therewith, such as a fence 46 (see Figure 1). The pressure plate 21 has on its lower edge a thin bottom plate 41 which swings in and out on a supporting plate 42. The plate 42 is secured by screws 43 to the frame F, as shown in Figure 2.

Practical operation

In the operation of my article compressing mechanism, when the wrapping machine is in operation the pockets 14 move intermittently in the direction of the arrow 18 and while they are in stopped position the shaft 19 rocks through one cycle to effect a wrapping operation of the bar B and card C in one of the pockets 14, as described in my copending application, Serial No. 317,370. At the same time the rock shaft 19, through the elements 22, 23, 24, 25, 26, 30, 31 and 34, moves the pressure plate 20 downwardly from the position of Figure 2 to the position of Figure 3 and simultaneously moves the pressure plate 21 toward the right for compressing an oversize bar B as for instance from the full line position of Figure 2 to the dotted line position therein, which is represented by a full line position in Figure 3. The bar B is now of the proper size to pass readily through the machine and the pressure plates 20 and 21 are returned to their initial positions of Figure 2, whereupon the next advance of the conveyer 13—14 takes place. Articles such as candy bars or the like may thus be readily sized for passage through the machine if they are not initially too much oversize, as, of course, it is undesirable to compress the bars so much that they become broken.

During the compressing operation, the bottom of the pocket 14 opposes the pressure plate 20 while a rail or fence 44 opposes the pressure plate 21. The fence 44 has a bottom flange 45 to support the card C and the bar B against bending downwardly at one end, while the plate 41 of the pressure plate 21 prevents such undesirable bending downwardly of the other end. After the bar has been compressed it is moved on toward wrapping position, passing between the fence 44 and the fence 46 on the opposite side from the fence 44. The fence 46 is so located that it gives clearance for the end of the compressed bar after compression has been accomplished by the pressure plate 21.

Some changes may be made in the construction and arrangement of the parts of my device without departing from the real spirit and purpose of my invention, and it is my intention to cover by my claims any modified forms of structure or use of mechanical equivalents which may be reason-

ably included within their scope without sacrificing any of the advantages thereof.

I claim as my invention:

1. In an article compressing mechanism for wrapping machines, the combination with an intermittently moving article conveyer having pockets for receiving articles and conveying them to a wrapping position; of mechanism for compressing oversize articles in said pockets comprising a pair of pressure plates, one for the top of the article and one for the end of the article, said pressure plates being pivotally mounted for movement from a position spaced from the top and end of an article in a pocket, to a position engaging the top and end of the article while the pocket for the article is in stopped position, the bottom of the pocket opposing said top pressure plate, and a fence at the end of the pocket to oppose said end pressure plate.
2. In an article compressing mechanism for wrapping machines, the combination with a frame, an article conveyer movable relative thereto and having pockets for receiving articles and conveying them to a wrapping position; of mechanism for compressing oversize articles in the successive pockets comprising a pair of pressure plates supported on said frame for movement relative thereto, one pressure plate being for the top of the article and the other one being for the end of the article, said pressure plates being mounted for movement from a position spaced from the top and end of an article in a pocket when the pocket is stopped relative to said frame, to a position engaging the top and end of the article if the article is oversize, and means at the bottom and opposite end of the article opposing said top and end pressure plates.
3. In an article compressing mechanism for wrapping machines, the combination with an intermittently moving article conveyer having pockets for receiving articles and conveying them to a wrapping position; of stationarily mounted mechanism for compressing oversize articles in said pockets comprising a pair of pressure plates, one for the top of the article and one for the end of the article, and means timed with the movement of said conveyer to move said pressure plates to a position engaging the top and end of an article in one of said pockets while said conveyer is in stopped position, the bottom of each pocket opposing said top pressure plate, and a stationary fence at the end of the pocket to oppose the end pressure plate.
4. In an article compressing mechanism for wrapping machines, the combination with an article conveyer having pockets for receiving articles and conveying them to a wrapping position; of a single mechanism for compressing articles in said pockets successively comprising a pair of pressure plates, one for the top of the article and one for the end of the article, and means timed with the movement of said conveyer to move said pressure plates to a position engaging the top and end of an article in one of said pockets.
5. In a device of the class described, the combination with an intermittently movable article conveyer having pockets for receiving articles and conveying the same to a wrapping position; of mechanism for compressing oversize articles in said pockets comprising a pivotal axis element parallel to the direction of travel of the conveyer, a first pressure plate pivotally mounted thereon, means operable from the mechanism for intermittently moving said conveyer to effect swinging

of said first pressure plate to a position engaging the top of an article in a pocket of said conveyer which pocket is in stopped position, said first pressure plate compressing the article with the bottom of the pocket opposing such compression, a second pivotal axis element in a plane at right angles to the plane of said first pivotal axis element, a second pressure plate pivotally mounted thereon, means operable from said first pressure plate to swing said second pressure plate to a position engaging the end of the article in said pocket which is in stopped position, and a fence opposite said second pressure plate to oppose the movement of said second pressure plate.

6. An article compressing mechanism for a wrapping machine comprising the combination with an article conveyer having pockets for receiving articles and conveying the same to a wrapping position; of mechanism for compressing oversize articles in the successive pockets comprising a first pressure plate mounted on a pivot axis parallel to the direction of travel of the conveyer, means operable from the mechanism for moving said conveyer to effect swinging of said first pressure plate to a position engaging the top of an article in one of the pockets of said conveyer, a second pressure plate mounted on a pivot axis in a plane at right angles to the plane of the first pivot axis, and means operable from said first pressure plate to swing said second pressure plate to a position engaging the end of the article in said one of said pockets.

7. An article compressing mechanism of the class described comprising the combination with an article conveyer having a series of pockets for receiving an article; of mechanism for compressing successive oversize articles in said pockets comprising a first pressure plate, means operable from the mechanism for moving said conveyer to effect movement of said pressure plate to a position engaging one surface of an article in one of said pockets and compressing said article, a second pressure plate, and means operable from said mechanism for moving said conveyer to move said second pressure plate to a position engaging another surface of said article at right angles to said first surface.

8. An article compressing mechanism for articles being wrapped in a wrapping machine comprising the combination with an intermittently movable article conveyer having pockets for receiving articles and conveying the same to a wrapping position; of mechanism for compressing oversize articles while in the successive pockets comprising a pair of pivotal axis elements, a pressure plate pivotally mounted on each of said piv-

tal axis elements, a link connection with an oscillatable part of the wrapping machine mechanism which oscillates in timed relation to the intermittent movement of said conveyer, said link connection effecting movement of one of said pressure plates and said pressure plate effecting simultaneous movement of the other pressure plate to positions for engaging two sides of the article at right angles to each other, and stationary means opposing each of the pressure plates at the time they move to article compressing position, whereby the pressure plates compress the article if it is oversize.

9. An article compressing mechanism for a wrapping machine of the class described comprising the combination with an intermittently rocking shaft and an intermittently movable article conveyer having pockets for receiving articles and conveying the same individually to a wrapping position; of mechanism for compressing oversize articles while in said pockets comprising a pair of pressure plates mounted for movement toward an article in one of said pockets, link connections between said rock shaft and said pressure plates, said link connections effecting simultaneous movement of said pressure plates to positions for engaging two sides of said article at right angles to each other.

10. An article compressing mechanism for a wrapping machine comprising the combination with an intermittently movable article conveyer having pockets for receiving articles and conveying the same to a wrapping position; of mechanism for compressing oversize articles in said pockets comprising a pair of pressure plates, a link connected with an oscillatable part of the wrapping machine mechanism which oscillates in timed relation to the intermittent movement of said conveyer, a bell crank connected with said link, a second link connecting said bell crank to one of said pressure plates, and a link connection between said one of said pressure plates and the other one.

11. Article compressing mechanism in combination with an intermittently moving article conveyer having pockets for receiving articles, comprising a pair of pressure plates, one for the top of an article in one of said pockets and one for the end of the article, said pressure plates being pivotally mounted for movement from a position spaced from the top and end of said article to a position engaging the article if the article is oversize, said end pressure plate having a supporting blade under the article in opposition to said top pressure plate.

OSCAR SANDBERG.
